UNITED STATES PATENT OFFICE.

JOHN GELOSO, OF NEW YORK, N. Y.

DESIGN FOR AN ESCUTCHEON PLATE FOR A VERNIER DIAL.

Application filed November 16, 1927. Serial No. 24,145. Term of patent 3½ years.

To all whom it may concern:

Be it known that I, JOHN GELOSO, a citizen of the Kingdom of Italy, residing at 417 East 14th Street, in the city, county, and State of New York, have invented a new, original, and ornamental Design for Escutcheon Plates for Vernier Dials, of which the following is a

specification, reference being had to the accompanying drawing, forming part thereof.

The figure is a front view of an escutcheon plate for vernier dials, showing my new design.

I regard as the dominant feature of my design the marginal design included between the central openings and the outer edge.

The ornamentation partially shown is to be understood to be repeated around the border in symmetrical fashion.

I claim:

The ornamental design for an escutcheon plate for a vernier dial, as shown and described.

JOHN GELOSO.
